[57] CLAIM

The ornamental design for the waterproof toilet paper holder, as shown and described.

DESCRIPTION

FIG. 1 is a front elevational view of the waterproof toilet paper holder showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The dotted lines showing of a roll of toilet paper in FIGS. 1 and 2 is for illustrative purposes only and forms no part of the claimed design.

FIG. 4

FIG. 6
